The ornamental design for a toothbrush, as shown and described.

DESCRIPTION

FIG. 1 is a front perspective of the toothbrush; showing my new design;

FIG. 2 is a front view thereof;

FIG. 3 is a left side view thereof;

FIG. 4 is a back view thereof;

FIG. 5 is a right view thereof;

FIG. 6 is a top plan view thereof;

FIG. 7 is a bottom plan view thereof; and,

FIG. 8 is a sectional view taken along line 8-8 of FIG. 4. The bodies of the toothbrushes are transparent; the parts shown in the broken lines form no part of the claimed designs; the shading shown in the FIGS. 1, and 7 represent the surfaces of the claimed design, and does not represent its surface ornamentation; FIG. 8 is a cross-sectional view of the back view 4.

In the drawings, the broken lines are for the purpose of illustrating portions of the toothbrush that form no part of the claimed design.
